DESIGN FOR A TREATMENT CHAIR

Henry J. Kalter, New York, N. Y.

Application June 14, 1935, Serial No. 57,258

Term of patent 7 years

To all whom it may concern:

Be it known that I, Henry J. Kalter, a citizen of Austria, residing at New York, county of Bronx, and State of New York, have invented a new, original, and ornamental Design for a Treatment Chair, of which the following is a specification, reference being had to the accompanying drawing, forming part thereof.

Figure 1 is a perspective view of a treatment chair, showing my new design.

Figure 2 is a side elevational view, and Figure 3 is a top plan view of the same.

I claim:

The ornamental design for a treatment chair, as shown.

HENRY J. KALTER.
